UNITED STATES PATENT OFFICE

HARVEY D. GEYER, OF DAYTON, OHIO, ASSIGNOR TO THE INLAND MANUFACTURING CORPORATION, OF DAYTON, OHIO, A CORPORATION OF DELAWARE

WATER-COOLER CABINET

Application filed August 29, 1927. Serial No. 216,115.

This invention relates to cabinets for water coolers or similar refrigerating cabinets.

An object of this invention is to provide a water cooler cabinet having separate molded side panels of plastic material which can be produced in quantity at a reduced cost and easily assembled together to form a complete box of neat outside appearance and good heat insulating qualities.

Other features of this invention are: (1) the joints between the separate panels can be readily fused together by means of a suitable hot iron pressed against the corners of the cabinet to give the appearance of a cabinet molded in one piece and to completely seal off the jacket space containing the ground cork or other heat insulating material whereby moisture is prevented from entering said jacket space and causing deterioration of the insulating material; (2) the back panel is provided with an interior lining or seal plate whereby this back panel is readily removable together with the heat insulating material therein in order to obtain access at any time to the face of the cooling unit for making duct connections thereto or for originally assembling the cooling unit in place; (3) the top panel or cover is readily removable at any time for cleaning the water tank, and rests upon a soft rubber gasket retained within a groove on the top edge of the side panels to give an air seal between the interior of the water tank and the outside air.

Further objects and advantages of the present invention will be apparent from the following description, reference being had to the accompanying drawings, wherein a preferred form of embodiment of the present invention is clearly shown.

In the drawings:

Fig. 1 is in part a plan view of the water cooler with the water bottle removed and in part a horizontal section on line 1-1 of Fig. 2.

Fig. 2 shows on the left side a side elevation of the water cooler, and on the right side a vertical section on the center line thereof.

Similar reference characters refer to similar parts throughout the several views.

The water tank 10 (preferably made from

sheet metal) has an open top, the sides being turned outwardly at the top to form the flanges 11. The four vertical panels and the bottom panel are all molded separately to the form illustrated from a suitable bituminous plastic compound, preferably such as the compound described and claimed in my copending application, Serial No. 169,669, filed February 19, 1927. All the vertical panels 5, 6, 7 and 8 have thickened marginal portions 12 having mitered edges 13 which abut one another with a neat fit and are rigidly secured together with small diagonally disposed stove bolts 14 and nuts 15, suitably spaced apart. These bolts 14 have their heads 60 countersunk into the molded material and the nuts 15 countersunk into the molded material and after the panels are secured together the countersunk holes are filled with a suitable sealing plastic material 16 to present a finished appearance and to completely 65 seal the joint. The inner edges of the marginal portions 12 abut the corners of the sheet metal tank 10, as clearly shown at 17, and thus the tank 10 is rigidly retained in place within the molded cabinet. The vertical joints between the mitered edges 13 are preferably 70 fused together by pressing a suitable hot iron against them with sufficient heat and pressure to cause the bituminous material to flow together. By this means the cabinet is given 75 the appearance of being molded in one piece, and also the interior heat insulating jacket is completely sealed off whereby moisture is prevented from condensing within the ground cork or other heat insulating material and 80 rotting the same.

The weight of the tank 10 and its contents rests upon the bottom panel 20 whose marginal portions 12 are similar to those of the vertical panels with the exception that small shoulders 21 are provided therein to receive the bottom sealing plate 22, as shown in Fig. 2. The interior jacket space 23 between the sealing plate 22 and the bottom wall of panel 20 is filled with ground cork, or other suitable heat insulating material, before the plate 22 is fixed in place. Preferably this plate 22 is formed from a bituminous composition similar to that from which the other molded panels are formed. The bottom panel 20 has 95 100

a mitered joint with the vertical panels similar to the vertical corner joints between the vertical panels, as clearly shown in Fig. 2.

The four vertical panels, 5, 6, 7 and 8 all have top marginal portions 25 which abut the side walls of tank 10 immediately under the flanges 11 and which are preferably recessed to receive the flanges 11. The top surface of these portions 25 have a gasket groove 26 molded therein adapted to receive a continuous soft rubber gasket 27.

The molded cover panel 30 has a flange 31 which rests upon the rubber gasket 27, thus forming an air seal for the interior of tank 10. The cover 30 has a central aperture 32 for receiving the neck of the up-turned water bottle 33. A soft rubber gasket 35 fits snugly over a raised bead around the periphery of the aperture 32 and receives the weight of the water bottle 33, as will be clear from Fig. 2. This gasket 35 provides an air seal around the aperture 32. Cover 30 has an annular jacket chamber 36 molded therein which is filled with ground cork and sealed up by the annular inner seal plate 37 to form an integral cover. This seal plate 37 is preferably formed from the same or similar bituminous compound as the cover 30 and can be retained in place with small nails, after which the joints are sealed by fusing the cracks together with a hot iron. The cover will then be in effect a one-piece cover with a hollow interior filled with cork.

The back vertical panel 8 is provided with an inner seal plate 9 of molded material which retains the ground cork 18 in place when the back panel 8 is removed. This seal plate 9 may be nailed with small nails to the panel 8 and the joints then sealed by fusing the cracks together, as described above for the cover. This back panel 8 may be easily removed as a unit simply by removing with a screw driver the small stove bolts 14 which are left unsealed by the plugs 16 for the purpose of easy removal. Access is thus had to the water tank 10 for originally assembling in place therein the cooling unit 40, or for making the proper connections thereto of the refrigerant ducts 41 and 42. This back panel 8 is suitably cut away at 43 to clear the duct connections. The ducts 41 and 42 which lead to the compressor preferably extend downwardly through a small hole 44 provided therefor through the thickened flanges 12 of the back panel 8 and the bottom panel 20. Preferably a soft rubber gasket 45 is interposed between the sealing plate 9 of the back panel 8 and the sheet metal tank 10.

It will be noted that the three vertical panels 5, 6 and 7 dispense with inner seal plates and that the heat insulating cork 24 is in direct contact with the sheet metal tank 10. This cork 24 may, if desired, be loose ground cork and inserted in position in the following manner: the four vertical panels

5, 6, 7 and 8 are first assembled together by means of the diagonal stove bolts 14, the back panel 8 first having the cork 18 and the seal plate 9 fixed thereto; the sheet metal tank 10 (without the cooling unit 40) is set upon a table in inverted position and the four panels 5, 6, 7 and 8 telescoped thereupon as a unit until the bottom of tank 10 clears the lower flange portions 12 of the vertical panels 5, 6, 7 and 8 by only an inch or so; the loose ground cork can then be packed into the three jacket chambers 24 by being inserted through the three narrow clearance spaces between the bottom of tank 10 and the inner corners of the flange portions 12 of the panels, after which the tank 10 is telescoped to its normal position at which its bottom corners abut these flange portions 12 (see Fig. 2); the bottom panel 20, with the cork 23 and the seal plate 22 fixed in place, is then secured in place by the bolts 14 to complete the cabinet.

The front panel 5 has a boss 4 molded integrally therewith through which the pipe nipple 50 extends. Nipple 50 is threaded into a flange 51 fixed to the sheet metal tank 10 and its outwardly projecting end has a water faucet 52 threaded thereon. A drain nipple 55 is fixed to the bottom of tank 10 and projects downwardly through a hole provided therefor. A drain cock 56 is screwed to its lower end. A molded soft rubber flange or moulding 60 may be provided at the bottom edge of the cabinet to enhance its appearance as well as to provide a water seal around the edge of the cabinet when it rests upon the flat surface of a table or stand.

While the form of embodiment of the present invention as herein disclosed, constitutes a preferred form, it is to be understood that other forms might be adopted, all coming within the scope of the claims which follow.

What is claimed is as follows:

1. In a water cooler, a metal water tank having an open top, separate molded panels enclosing said tank and forming a cabinet surrounding and supporting said tank, said molded panels having thickened margins mutually abutting each other and the corners of said tank, heat insulating material filling the space between the panel walls and tank walls, and a removable heat insulating top having a flange resting upon the top edges of the side panels.

2. In a water cooler, a sheet metal water tank having flat walls, separate molded panels having inwardly projecting marginal flanges abutting the corners of said metal tank and firmly secured in place and thereby forming chambers between said flat metal walls and the molded panels, and heat insulating material filling said chambers.

3. In a water cooler, a sheet metal water tank having flat walls, separate molded panels having inwardly projecting marginal flanges abutting the corners of said metal

tank and firmly secured in place and thereby forming chambers between said flat metal walls and the molded panels, and heat insulating material filling said chambers, and a removable heat insulating top resting by gravity upon the top edges of the vertical walls.

4. A water cooler comprising: a sheet metal water tank, separate molded side panels of bituminous material each having inwardly projecting marginal portions mutually abutting each other and the vertical corners of said tank and thereby forming jacket chambers between the metal walls and said panels, insulating material filling said chambers, and a molded bottom panel fixed in place upon the bottom of said tank, said bottom panel having a jacket chamber molded therein, insulating material in said jacket chamber, and an inner lining covering said insulating material.

5. In a heat-insulated cabinet, in combination, a sheet metal tank having flat side walls, separately molded side panels of bituminous composition having inwardly projecting marginal flanges abutting the corners of said metal side walls and rigidly fixed in place and thereby forming relatively shallow chambers between said flat walls and said panels, heat insulating material filling said chambers, and a heat insulating bottom panel fixed upon the bottom of said metal tank and abutting the bottom edges of said side panels.

6. In a heat-insulated cabinet, in combination, a sheet metal tank having flat side walls, separately molded side panels of bituminous composition having inwardly projecting marginal flanges abutting the corners of said metal side walls, and mitered together at their contacting edges, bolts extending diagonally through these mitered joints to rigidly fix said panels together, and a heat-insulating bottom panel at the bottom of said metal tank and held fixed in place by bolts extending into the lower edges of said side panels.

In testimony whereof I hereto affix my signature.

HARVEY D. GEYER.
